The ornamental design for a sample collector device, as shown and described.

DESCRIPTION

FIG. 1 is a front view of a sample collector device showing our new design, the side views and rear view being the same as the front view;

FIG. 2 is a top perspective view thereof;

FIG. 3 is a bottom perspective view thereof;

FIG. 4 is a side, top perspective view;

FIG. 5 is a side, bottom perspective view;

FIG. 6 is a top view thereof;

FIG. 7 is a bottom view thereof; and,

FIG. 8 is an exploded view thereof.
